UNITED STATES PATENT OFFICE.

CONRAD GAHR, OF NEWARK, NEW JERSEY.

IMPROVEMENT IN APPARATUS FOR CUTTING AND EMBOSSED LEATHER STRAPS.

Specification forming part of Letters Patent No. 178,845, dated June 20, 1876; application filed December 10, 1875.

To all whom it may concern:

Be it known that I, CONRAD GAHR, of Newark, in the county of Essex and State of New Jersey, have invented a new and Improved Process of, and Apparatus for, Cutting, Raising, and Creasing Harness Straps, Layers, &c., of which the following is a specification:

This invention has for its object to produce means for simultaneously cutting out, creasing, raising, and, if desired, also embossing, the straps or layers used on breast-collars, breechings, belly-bands, martingales, turn-backs, back-bands, trace-bearers, and other parts of harness.

The invention consists principally in combining a pair of knives with a grooved block, to which said knives are rigidly attached, said grooved block serving to crease and raise the strap at the same time that the knives cut it into shape. Heretofore the straps were cut by hand in conformity with a pattern laid upon them, and were subsequently raised in the middle by being pressed by hand into the hollow of a block, and finally creased by a creasing-tool. These manipulations consumed much time, and were apt to draw the strap out of shape. By performing all these functions at one movement, and by machinery, a perfect strap is produced at a comparatively small expense.

My invention also consists in making the concave raising-block sectional to allow the alternate employment on the same block of several embossing-tools.

In the accompanying drawing, Figure 1 represents an end view of the raising and cutting block. Fig. 2 is a side view of the same. Fig. 3 is an end view thereof, showing a modification in the method of raising the strap. Fig. 4 is a bottom view thereof. Fig. 5 is a face view of a strap, cut, creased, and raised by the same. Fig. 6 is a vertical transverse section of the raising and cutting block, showing it provided with a removable embossing tool. Figs. 7 and 8 are two face views of straps that have been cut and raised by the same block, but are nevertheless differently embossed.

Similar letters of reference indicate corresponding parts in all the figures.

The letter A in the drawing represents a metallic block as long and wide as the strap to be cut, and flanked at the sides by two knives, B B, of the form which is to be imparted to the edges of the strap. The knives are, by means of screws, rivets, or other means, attached to the sides of the block A, and their cutting-edges project beyond the intermediate surface of said block. This intermediate surface is grooved or hollowed in the direction of its length for raising the leather strap to be cut—that is, imparting a convex surface thereto—and has near the knives one or more narrow projecting ribs, a, wherewith to crease the strap in the desired manner, all of which is clearly indicated in Figs. 1, 2, 3, and 4.

For use, the block A is attached to a suitable plunger, and the strap C to be cut and pressed placed upon a table, D, as in Fig. 1. This table should have a convex projection, b, under the groove d of the block, for the purpose of aiding in raising the leather into said groove d as soon as the block descends. The leather to be cut into a strap is placed upon the table D lengthwise over the rib b, and the block A then brought down upon it, so that the knives B B will cut the strap of the required width and outline, the ribs a a meanwhile creating the surface of the strap, and the rib b raising the strap into the groove d. Thus at one operation the labor of shaping the strap is completed.

The modification shown in Fig. 3 has reference to the process of raising the strap, and consists in placing a narrow strip, e, of leather or equivalent material upon the table D, beneath the leather C, and under and in line with the groove d, in which case the rib b is dispensed with. This narrow strip e will properly raise the leather into the groove, and may afterward remain under the completed strap C between same and a suitable back piece or lining, f. Where the leather is to be but slightly raised the rib b and groove e may be dispensed with.

When the strap is to be also embossed I form suitable embossing ribs or depressions g g on the face of the block A between the knives B B. But as the same size and form of strap are frequently desired with different embellishments, as indicated in Figs. 7 and 8, I

propose to make that part *h* of the block *A* on which the embossing ornaments *g* are formed removable from said block, as indicated in Fig. 6, so that it may be displaced by another piece, *h*, of the same style, but having different embossing ornaments. The embossing-section *h* can be fastened in the hollow of the block *A*, into which it is fitted by suitable screws or other means.

I claim as my invention—

1. The combined cutting, raising, and creasing tool, composed of the block *A* and knives

B B, the surface of the block having the creasing-ribs *a* and the raising-groove *d* between the knives, substantially as specified.

2. The combination of the shaping-block *A*, which carries the knives *B B*, with the removable embossing-section *h*, substantially as specified.

CONRAD GAHR.
